RECEPTACLE

Iver M. Johnson, Attleboro, Mass., assignor to
 Evans Case Company, North Attleboro, Mass.,
 a corporation of Massachusetts

Application November 23, 1933, Serial No. 699,446

10 Claims. (Cl. 206—41)

The invention relates generally to receptacles which may be adapted for use for any purpose. The invention is particularly adaptable to cigarette cases and it will be described in its application thereto.

One common type of cigarette case which is carried in the pocket or handbag includes two members hinged together so that when they are closed the cigarettes are entirely enclosed and protected but when they are open the cigarettes are available for withdrawal and use. The cigarettes may be held in position in the open case by a spring pressed arm resting against them. Ordinarily the cigarette must be bent or deformed to withdraw it or the arm itself must be released or raised thus freeing all of the cigarettes held by it and tending to allow them to become disarranged or in disorder. It is a purpose of the present invention to overcome this defect.

Such articles which are in more or less constant use and are constantly carried about are preferably ornamented and made acceptable to the eye. This may be done by plating, painting, engraving, enamelling, setting with various materials or other treatments. In general the treatments of the various portions of the article must be harmonious and they must be of such a character that the application of one treatment to one portion of the article will not interfere with the application of the treatment to any other portion of the article. This places certain limitations upon the character of treatment to be given to an article or at least makes the treatment difficult and expensive. Obviously if portions of an article are to be enamelled, for instance no other portion of the article at the time the enamelling is made can be of a character to be harmed or deformed by the temperatures required to finish the enamel. It is a purpose of the present invention to provide greater freedom in variations of ornamentation applied to various portions of such an article.

In the accompanying drawing Figure 1 is a plan view of an opened cigarette case illustrating the invention. Fig. 2 is a vertical section through one of the members of the cigarette case. Fig. 3 is an enlarged fragmentary plan view of one end of a member expanded, a portion being shown in section to illustrate the construction. Fig. 4 is a fragmentary transverse section of a closed cigarette case illustrating the catch and the keeper adapted to hold the two members closed. Fig. 5 is a transverse section of a case partially opened.

The cigarette case comprises two members 10 and 11 hinged together at 12 along one of their

sides. Cigarettes 13 are shown in Fig. 1 held in place by hinged arms 14 and 15 which are held against the cigarettes by the ends of a coil spring 16 carried by the pintle of the hinge 12. Two of the cigarettes are shown out of position to illustrate a phase of the invention to be referred to later. A catch 17 of resilient material is fastened to the edge of the member 10 and when the case is closed the catch 17 engages a keeper 18 here shown as a turned in portion integral with the member 11. In the operation which makes the shell blank, the keeper or catch lip 18 is formed turned outward and a subsequent squeezing operation turns the lip inward to act as a catch without leaving any surplus of stock and eliminates the necessity of using a pinned on catch piece which may cause the head of the pin to show on the outside of the finished case.

At the upper end of the member 10 and the opposite or lower end of the member 11 is secured an end piece 19 which is provided with an in-turned corner 20 against which the corresponding end of the member 10 or 11 seats and to which it is fastened. It will be understood that the end piece 19 is fastened throughout one half of its contour to the member 10 or 11. The other half of the seat 20 forms a seat against which the free end of the member 10 or 11 engages when the case is closed. This is clearly shown in Fig. 5. As illustrated in Fig. 3 the end pieces 19 may be inserted and fastened in place in the members 10 and 11. This completes the interior of the cigarette case the end pieces 19 forming seats against which the cigarettes in the members 10 and 11 may seat or be aligned. The opposite ends of the members 10 and 11, being the lower end of 10 and the upper end of 11 as illustrated in Fig. 1, are plain, smooth and unobstructed and they are formed to fit against the seat 20 but providing no obstruction to the withdrawal of cigarettes. As illustrated in Fig. 1 the cigarette 13a may be freely withdrawn downward from its place in the member 10 and this without necessarily releasing the holding arm 14 or otherwise disturbing the other cigarettes in the member 10. Likewise any of the cigarettes in the member 11 as illustrated at 13b in Fig. 1 may be withdrawn upward, over and through the smooth unobstructed end of the member 11 even without lifting or releasing the arm 15 and without disturbing the other cigarettes in the member 11. This allows cigarettes in the two sides of the case to be withdrawn in opposite directions and since the open ends of the members 10 and 11 are smooth and unobstructed the ciga-

rette being withdrawn need not be bent, deflected, deformed or otherwise damaged or injured.

In addition to the seat 20 provided on the end pieces 19 there is an upturned surrounding edge 21 which may be employed to receive a member 22 which after being inserted may be held in place by rolled in edges 23 as indicated more clearly in Fig. 2. The member 22 obviously may be of the same material as the rest of the cigarette case or it may 10 be of a different material. It may carry any suitable device or may be decorated to match the rest of the cigarette case or it may be decorated to contrast or harmonize with the rest of the cigarette case. The piece 22 being separate initially 15 from the rest of the cigarette case may be treated in any suitable way, it may be covered with enamel or cloisonné or any other desired ornamentation which may require a treatment which may not be necessary for the rest of the case or 20 which may be deleterious to the rest of the case. The piece 22 might be of precious metals or of mother-of-pearl or of any other suitable or desired material and may be surely inserted in place in the end of the case by merely rolling in the 25 edge 23 which being a simple operation will not injure or destroy the piece 22 or the ornamentation carried by it. It will be obvious that the end piece 19 not only closes the end of the box and also forms a flat seat against which the cigarettes 30 may rest but also forms a seating for an ornamental end piece. As illustrated the inner portion of the end 19 is flat so as to form a smooth flat seat for the cigarettes and the outer piece 22 may be of any suitable or desired form and may 35 be provided with or form part of any desired ornamentation or other device but is shown curved to form a comfortable desired external end.

The invention is not limited to the specific 40 details shown as to form, shape, proportions etc. but may be embodied in various other structures.

I claim as my invention:

1. A cigarette case comprising two members each adapted to receive and hold cigarettes, a 45 hinge between the members allowing them to close and bring the sides holding the cigarettes facing each other, an end piece on one end of each member against which the cigarettes may rest and each having a seat against which the end of 50 the other member rests when the case is closed, and each member having a smooth unclosed and unobstructed end opposite its end piece.

2. A cigarette case comprising two members each adapted to receive and hold cigarettes, a 55 spring held hinged arm on each member overlying the cigarettes and holding them in place, a hinge between the members allowing them to close and bring the sides holding the cigarettes facing each other, a latch on the engaging edge 60 of one member, an integral inturned keeper for the latch on the adjacent edge of the other member, an end piece on one end of each member

against which the cigarettes may rest and each having a seat against which the end of the other member rests when the case is closed, each member having a smooth unclosed and unobstructed end opposite its end piece, an upset seat in each end piece, a separate piece of material in the seat, and a rolled in edge holding the piece in its seat. 80

3. A section of a receptacle comprising an upset portion for attachment to another section of the receptacle and forming a seat for a third cooperating section of the receptacle and an upturned border adapted when rolled in to receive and hold in place a separate member. 85

4. Means for decorating a receptacle comprising an upturned edge on a wall of the receptacle 90 one edge of which is normally free and a separate ornament element on the wall and held in place by rolling in the upturned edge.

5. A section of a receptacle comprising an upset portion a part of which is for attachment to another section of the receptacle and the rest of which forms a seat for a third cooperating section of the receptacle, and an upturned border adapted when rolled in to receive and hold in place a separate member. 95

6. A cigarette case comprising two members each adapted to receive and hold cigarettes, each member having at one end a seat against which the cigarettes may rest, an upturned edge on the seat and a separate ornament on the seat held 100 in place by rolling in the upturned edge.

7. A cigarette case comprising two members each adapted to receive and hold cigarettes, each member having at one end a seat against which the cigarettes may rest, the seat also comprising 105 a seat for the other member of the receptacle and an upturned border adapted when rolled in to receive and hold in place a separate member.

8. A cigarette case comprising two members hinged together to form the case each adapted to 110 receive and hold cigarettes, each member having at one end a seat against which the cigarettes may rest, said seat having integral means on its outer side to receive and hold a separate member and each member being smooth, unclosed and unob- 115 structed at the end opposite its seat.

9. A cigarette case comprising two members hinged together to form the case, one member adapted to receive and hold cigarettes and having at one end a seat against which the cigarettes 120 may rest, said seat having integral means on its outer side to receive and hold a separate member. 125

10. A cigarette case comprising two members hinged together to form the case, one member adapted to receive and hold cigarettes and having 130 at one end a seat against which the cigarettes may rest, said seat having integral means on its outer side to receive and hold a separate member and being smooth, unclosed and unobstructed at the end opposite its seat. 135

IVER M. JOHNSON.
